GUN COMPASS ATTACHMENT

Frank J. Kaszynski, Wilmington, Mass.

Application October 25, 1952, Serial No. 316,856

1 Claim. (Cl. 42—71)

This invention relates to guns and to attachments therefor and more especially to attachment of a compass to a gun stock.

It is important for a hunter or woodsman to have with him at all times a compass for it is quite easy for even an experienced woodsman or hunter to become confused as to direction and become lost if not for a prolonged period at least for a sufficient length of time to make it annoying and inconvenient. While the average conscientious hunter will carry a compass in his pocket, it is very easy to forget to carry it or to lose it, accordingly it has been suggested that a compass might be attached to a part of his equipment, such as his gun. The attachment of the compass to a gun, however, is limited to the stock since if located on or near the barrel or breech the metal of the gun will spoil the accuracy of the compass. It has been proposed to mount a compass on the side or top of the stock and according to one method of mounting a hole is bored in the side or top of the stock of sufficient depth to receive the body of the compass case and the latter is then pressed into it, usually with a coating of adhesive so that it will stay in place. While this is a perfectly effective way of mounting the compass so that it will remain permanently attached to the gun it is highly objectionable from the standpoint of the fastidious hunter for the reason that he cannot endure the thought of boring a hole in the gun stock. In fine guns the stock is made of a high grade walnut, such stocks being hand tooled to bring out the beauty of the grain and will cost in the neighborhood of two to four hundred dollars, sometimes much more. The average owner of such a gun cannot abide the idea of tampering with the stock to the extent of drilling holes in it for attachment of a compass for fear that through some inadvertence or lack of skill the stock may be spoiled. Furthermore, many gun stocks contain within them a part of the bolt chamber so that metal runs rearwardly into the gun stock and the proximity of this metal to a compass mounted on the stock spoils its accuracy.

The object of this invention is to provide means and a mode of attaching a compass to a gun stock without boring holes in the stock itself and in such a position as not to be effected by the metal of the gun. A further object is to provide a very simple means for attaching the compass to the stock which will be inexpensive to manufacture, easy to install, permanent in its nature and will not deface or spoil the appearance of the gun in any respects. Most guns have a pistol grip and in accordance with this invention the compass is fastened to the butt end of the pistol grip. As illustrated the conventional butt plate of the pistol grip is removed and replaced by a plate of corresponding shape which has a recess in it within which may be pressed a compass and a hole at the bottom of the recess through which a screw may be inserted for attaching it to the butt. The plate is itself comprised of a non-metallic material such as a hardenable plastic and a non-magnetic screw such as brass or bronze is employed for fixing it in place. An adhesive may be applied to the case prior to pressing

it into the recess to insure permanent anchorage. Alternatively, the inside wall of the recess may be grooved and a rubber or other resilient ring set into it so as to frictionally engage the wall of the compass when pressed into it.

The invention will now be described in greater detail with reference to the accompanying drawings wherein:

Fig. 1 is a side elevation of the stock of a rifle or gun of the kind which has a pistol grip showing the attachment applied thereto;

Fig. 2 is a plan view of the attaching plate for anchoring a compass to the pistol grip;

Fig. 3 is a vertical section taken on the line 3—3 of Fig. 2 showing the compass receiving recess;

Fig. 4 is a vertical section taken on the line 4—4 of Fig. 1;

Fig. 5 is a vertical section through a plate showing a modified compass receiving recess which has a locking groove in its wall;

Fig. 6 is a plan view of the bottom side of an attaching plate of modified construction; and

Fig. 7 is a section taken on the line 7—7 of Fig. 6.

Referring to the drawings (Fig. 1), there is shown a gun stock 10 of conventional shape comprised of walnut or some other fine, hard grained wood which in accordance with best gun making practice has a pistol grip 12 to which there is ordinarily attached a butt plate. In lieu of the conventional butt plate and in accordance with the present invention there is attached to the butt of the pistol grip a plate 14 which corresponds in shape to the conventional butt plate. The plate 14 is comprised of a non-metallic material, for example, hard rubber or one of the commercially available plastics molded to correspond in shape to the butt plate it is to replace. During molding a circular recess 16 is formed in its outer face of such depth as to receive a small compass 22. The bottom of the recess contains a central hole 18 through which may be placed a brass screw 20 for fastening the plate to the butt of the pistol grip as shown in Fig. 4. It is important of course, that both the plate 14 and screw 20 for attaching it in place should be of non-magnetic material.

In order to secure close engagement of the edges of the plate with the end of the pistol grip, the plate is preferably recessed as shown at 24 so that only a narrow margin 45 of its undersurface has contact with the wood of the grip. As thus constructed the compass 22 is usually forced into the recess 16 together with a small amount of adhesive, the excess being wiped off at the surface and under most conditions this will constitute a permanent fastening.

If it is not desirable to cement the compass in place or if climatic conditions are such that cement would deteriorate to the extent of allowing the compass to fall out, the wall of the plate as shown in Fig. 5 may have formed therein a locking groove 26 for reception of a resilient locking ring 28. Such a ring may be in the form of a rubber band or other non-metallic resilient material placed in the groove so that a portion projects beyond its surface. Thus when the compass case is forced into the recess it will squeeze the ring into the groove and the latter will frictionally hold the compass in place.

Figures 6 and 7 show a modified form of the plate wherein the recess 30 at the back side of the plate is enlarged so as to extend part way through the plate and within this recess there is located an island 32 having a hole 34 therein for the reception of the screw for attaching the plate to the pistol grip. The island 32 forms the bottom of the compass receiving recess 16 and is so located that when the latter is seated against it, its face will be substantially flush with the outer face of the plate.

Radial arms 36 formed integral with the island 32 and the walls of the recess 30 support the latter in place and form a rigid structure. An advantage of this latter structure is

that there is some economy in material and the plate is lightened somewhat without sacrifice of strength.

The advantages of the attachments as distinguished from setting the compass case into the side of the stock or the top is that it is not necessary to bore a hole in the stock and that when attached it appears to be no more than the conventional pistol grip plate and therefore does not mar the appearance of the gun, that it is in an out of the way position so that it cannot possibly interfere with the firing or use of the gun, that it is located well away from the metal of the gun so that it is not adversely affected and hence its accuracy will be unaffected and that it is a very simple inexpensive and easily mounted attachment which will secure the compass permanently in place without danger of loss.

It should be understood that the present disclosure is for the purpose of illustration only and that this invention includes all modifications and equivalents which fall within the scope of the appended claim.

I claim:

An anchor plate for attaching a compass to the butt of the pistol grip of a gun stock comprising a rigid non-metallic plate of generally oval shape having front and rear sides, said front side having a convex surface simulating in appearance the surface of a conventional butt plate, a circular well extending through the plate from front to rear for receiving the case of a compass, and a groove in the wall of the well for receiving a friction ring to hold the compass in the well, a raised shoulder at the rear side of

the plate extending marginally thereof, said shoulder providing a narrow annular bearing surface for contact with the marginal edge of the butt, an apertured hub situated centrally of the back concentric with the well, the rear face of the hub being situated below the edge of the shoulder and the front face being situated at the bottom of the well and constituting an abutment against which the bottom of the compass case rests when seated in the hole, said aperture at the front face of the hub being countersunk to receive the filleted head of a non-ferrous fastening screw for attaching the plate to the butt, and radial ribs connecting the hub to the plate, said ribs extending from the hub across the back to the inner wall of the shoulder, the inner ends of the ribs being integral with the hub, the inner edges of the ribs being integral with the rear surface of the plate, and the outer ends of the ribs being integral with the inner wall of the shoulder.
